COVER FOR SINKS PROVIDED WITH
SPRINKLING MEANS

Gunnar Fredrikson, Stockholm, Sweden

Application November 24, 1937, Serial No. 176,153
In Sweden October 20, 1936

5 Claims. (Cl. 141—9)

The present invention relates to covers for sinks provided with a sprinkling device and particularly to covers of the kind having a guide slot in which a sprinkling nozzle is moved to and fro during the sprinkling.

Covers of this kind have the drawback of necessitating the disjointing of the sprinkling nozzle, when the latter is removed from the cover. Further, a quick removal or replacing of the nozzle 10 in position over the sink is not possible. The invention aims at eliminating these drawbacks and is characterized, among other features, thereby that the guide slot, which separates the cover substantially along the center thereof into two 15 connected parts, extends to one edge of the cover so that the sprinkling nozzle can be inserted into and moved from said slot sidewise through the edge of the cover, the means connecting the two parts of the cover being disposed outside the continuous path of said nozzle in its movement through said edge and along said slot.

An embodiment of the invention is illustrated in the accompanying drawing.

Figure 1 shows a sink provided with a cover 25 viewed from above,

Figure 2 is a section on line II—II of Figure 1, and

Figure 3 is a section on line III—III, of Figure 2 on a larger scale.

In the drawing the sink is indicated by 1, the cover by 2, the guide slot, provided therein, by 3 and the sprinkling nozzle by 4. The sprinkling nozzle, which has an operating handle 9, is connected with the water main by means of a hose 5. The guide slot 3 is open at one or both end portions and the two parts of the cover separated by the slot are held together by means of a preferably downward directed yoke member 10 of a shape to allow passing of the sprinkling nozzle 30 when it is inserted into or removed from the guide slot sidewise through the edge of the cover. Along the guide slot, there are stationarily disposed parallel guides 11a which engage resiliently a guide block 11 secured to an intermediary member 8 connecting the sprinkling nozzle with the hose. In order to obtain a noiseless movement of the block when the sprinkling nozzle is moved to and fro in the guide slot the block is preferably made of wood, bakelite or the like. The friction surface between the block 11 and the guide member 11a is reduced by providing longitudinally extending inward projections 12 or the like on the guides 11a. By means of the guides 11a and the guide block 11 a steady guiding of the sprinkling nozzle is obtained, which is very important 40 because plates placed vertically and in trans-

verse direction of the sink on stands are thus sprayed equally on both sides.

The cover is flat and overlaps to some extent the edge of the sink. The flat shape of the cover provides a working surface over the whole dishwashing table when the sprinkling nozzle has been removed from the slot.

The cover is fixed to the rear wall of the sink by means of hinges 14 fixed to the underside of the cover and adapted to be pushed down into 10 grooves 13 in the rear wall thereof, so that the cover at choice may be swung open or entirely removed from the sink.

Having now described my invention, what I claim as new and desire to secure by Letters 15 Patent is:

1. In a dishwashing device a sprinkling nozzle, means to connect said nozzle to a water supply, a removable flat cover for a sink comprising two connected parts separated by a slot, and guide 20 means movable with said nozzle to guide it longitudinally of said slot below said cover, said slot extending to one edge of the cover, whereby the nozzle with said connecting means can be inserted into and removed from said slot sidewise through 25 the said edge of the cover, and the means connecting said two parts of the cover being disposed outside the continuous paths of said nozzle and first mentioned connecting means in their movement through said edge into and along said slot. 30

2. A dishwashing device as claimed in claim 1, in which said means for connecting the two parts of the cover include a downwardly projecting member having therein an opening terminating in said slot, said nozzle having a vertical cross-section 35 smaller than the area of said opening.

3. A dishwashing device as claimed in claim 1, in which said means for connecting the two parts of the cover include a downwardly projecting yoke disposed adjacent one end of said slot, said 40 nozzle having a vertical cross-section smaller than the area surrounded by said yoke.

4. In a dishwashing device, a cover for a sink having a longitudinal guide slot, a sprinkling nozzle, guide means movable with said nozzle to 45 guide it longitudinally of said slot below said cover, and resilient longitudinally extending guides depending from the longitudinal edges of said slot to engage said guide means on said nozzle.

5. A dishwashing device as claimed in claim 4, in which said guides have longitudinally extending inward projections to engage said guide means on a reduced surface.
